E. GRAH

CHAIN BOLT DEVICE

Filed March 2, 1922

UNITED STATES PATENT OFFICE.

EMIL GRAH, OF TOLEDO, OHIO.

CHAIN-BOLT DEVICE.

Application filed March 2, 1922. Serial No. 540,531.

To all whom it may concern:

Be it known that I, EMIL GRAH, a citizen of the United States of America, residing at Toledo, Lucas County, Ohio, have invented new and useful Chain-Bolt Devices, of which the following is a specification.

This invention relates to holding devices.

This invention has utility when incorporated in locks of the chain bolt type for doors and holding of swinging or hinged closures for slight opening only.

Referring to the drawings:

Fig. 1 is a fragmentary view of an embodiment of the invention in connection with a hinged door;

Fig. 2 is a side elevation, on an enlarged scale, of the bolt in hung position on the door jamb;

Fig. 3 is a plan view of the holding plate;

Fig. 4 is a section on the line IV—IV, of Fig. 3;

Fig. 5 is a fragmentary bottom plan view of the holding plate; and

Fig. 6 is a detail view of the bottom plan of the bolt.

Swing closure or door 1 is mounted by hinges 2 to swing into position against jamb 3 of a door frame. Mounted on this door frame by means of screws 4 is a mounting plate 5 terminating at its lower portion in a hook 6 upwardly open to receive head 7 having a tapered reverse portion 8 as a neck extending or connecting this head 7 with chain bolt 9. This chain bolt 9 has flexible connection by means of chain links 10 engaging in eye 11 of the plate 5 on the door jamb.

A holder or plate 12 is anchored by screws 13 in position on the door 1, preferably in a position about a horizontal plane from the plate 5 carried by the jamb. This plate 12 is provided with a seat 14 extending away from the plate 5. This seat 14 terminates in enlargement 15 having an angular register or key portion 16 for engaging a register portion 17 of the head 7 of the chain bolt 9. This means that in any assembly of the chain bolt 9 with the holder plate 12, the chain bolt must be brought into a peculiar angular position before the bolt head may enter for sliding along the seat 14 toward the plate 5.

The under side of this holder plate 12 is shown as provided near the seat portions 14, 15, with a pair of parallel cheeks 18 through which may extend bearing pin 19

for lever 20 normally thrust by spring 21 to hold enlarged head 22 as a closure for the bolt head receiving portion 15 of the seat 14 in the plate 12. To complete this closure of 60 the seat portions 14, 15, the head 22 is provided with a lug or key portion 23.

For placing the chain bolt 9 in locking position it is merely necessary to lift the bolt with its head 7 off the plate 5 and thrust the head 7 in the seat portion 15. When this bolt 9 has its head 7 provided with register portion 17 as a key, it is of course necessary to bring this bolt 9 to fit in such angular position before the head 7 may enter the seat portion 15 for sliding along the way 14 in the plate 12. Accordingly, when this bolt portion is held in angular position it will permit of insertion of this head 7 into this seat portion 15 for sliding along the way 14. 75 This thrusting action of the head 7 may of itself overcome the action of the spring 21 and remove closure 22 so that the bolt 9 as removed from the hook 6 may be simply and quietly placed in engaging position as to 80 the door 1. Should attempt be made to remove this bolt 9 from outside the closure, thrusting of the bolt 9 against the removable portion 22 causes the tapered portion 8 to ride under this closure 22 and more firmly 85 hold this closure 22 in position. To effect removal it is necessary that lever 20 be dropped to lower this closure 22 before the bolt 9 is brought into position along the way 14. 90

As a safety device this means that in a slight opening of the door it is not accessible for manipulation by anyone from the outside. There is accordingly, by a simple mechanism, produced a most effective safety 95 device.

What is claimed and it is desired to secure by Letters Patent is:

1. A holder plate provided with a seat, a bolt having a head for engagement with 100 said seat, connection to the bolt for effecting bolt travel as to the seat, said seat being provided with a bolt head receiving portion, a lever provided with a fulcrum intermediate its ends and providing a closure for 105 said portion, and a spring normally holding the lever in seat closing position.

2. A holder plate provided with a seat, a bolt having a head for engagement with said seat, connection to the bolt for effecting bolt travel as to the seat, said plate provided with means in addition to the connection 110

effecting travel of the head as to the seat for precluding bolt head ready removal, and a normal closure for a head receiving portion disposed in said seat against bolt head action,
5 there being means beyond the base of the plate and laterally of said seat, which means is manually operable to shift the closure to permit bolt head removal from said seat.

3. A holder plate provided with a seat, a
10 bolt having a head for engagement with said seat, connection to the bolt for effecting bolt travel as to the seat, said plate provided with means, in addition to the connection effecting travel of the head as to the seat, for precluding bolt head ready removal, and a spring thrown lever having a
15 fulcrum intermediate its length and embodying terminally a trigger normally closing the head receiving portion as to said
20 seat against bolt head action.

4. A holder plate provided with a seat, a

bolt having a head for engagement with said seat, connection to the bolt for effecting bolt travel as to the seat, said plate provided with means, in addition to the connection effecting travel of the head as to the seat, for precluding bolt head ready removal, and a lever pivoted to the plate intermediate the ends of the lever, said lever terminally providing normal closure for a head receiving portion in said seat, said bolt head, in being drawn toward said closure, having wedge coaction for maintaining the closure against bolt head removal.
30

5. A chain bolt having a key head, a holding plate for the bolt having a bolt head entry keyhold portion, and a lever pivoted to the plate intermediate the ends of the lever, said lever terminally providing normal closure for the portion.
35

In witness whereof I affix my signature.

EMIL GRAH.
